UNITED STATES PATENT OFFICE

WILLIAM J. MULLIGAN, OF PARKERSBURG, WEST VIRGINIA

CIRCUIT CLOSER

Application filed March 2, 1926. Serial No. 91,759.

This invention relates to a circuit closer forming a part of a combined fire and burglar alarm for use in the protection of buildings, one of the objects being to provide a 5 heat conductor suspended within the building so as to move freely, said heat conductor constituting means for directing heat against a fuse in the event of a fire so as to operate an alarm and also constituting means, when 10 shifted out of normal position, for sounding or operating the alarm.

A further object is to provide means whereby it becomes impossible to enter a window or a door of the building without 15 shifting said suspended member out of normal position and thereby operating the alarm.

A further object is to provide a suspended member of the kind mentioned which will 20 conduct heat to the fuse of the alarm mechanism from different parts of the building.

With the foregoing and other objects in view which will appear as the description 25 proceeds, the invention resides in the combination and arrangement of parts and in the details of construction hereinafter described and claimed, it being understood that changes in the precise embodiment of the invention herein disclosed may be made within 30 the scope of what is claimed without departing from the spirit of the invention.

In the accompanying drawings the preferred form of the invention has been shown.

In said drawings, 35 Figure 1 is a section through a portion of the building showing the present improvements installed therein.

Figure 2 is a section through the upper 40 portion of the pendant circuit closing structure.

Figure 3 is an enlarged section through the supporting arm of the pendant circuit closing structure.

Figure 4 is a section on line 4—4 Figure 3.

Figure 5 is a horizontal section through the upper portion of one of the cylindrical members of the pendant structure.

Figure 6 is a view more or less in diagram 50 of a portion of the pendant structure and the circuits controlled thereby.

Referring to the figures by characters of reference A designates a building structure at any suitable point in which is arranged a pipe 1 having one or more outlets 2 from which are extended tubular brackets 3. On 55 each of these brackets is mounted one end of a tubular arm 4, the meeting portions of the bracket and arm being preferably substantially circular as shown in Figure 4 and formed with teeth or serrations. A connecting bolt 5 is extended through the meeting portions of the arm and bracket for the purpose of holding the serrated portions in contact and maintaining the arm 4 extended at a desired angle from the brackets 3. A spring 60 6 may be mounted on the bolt 5 and housed within the arm 4 for the purpose of holding the arm pressed yieldingly upon the bracket. The meeting portions of the arm and bracket are provided with registering openings 7. 70

The free end of arm 4 is provided with a hook 8 and this hook serves to support a link 9 formed of a tube. This link has an opening 10 in the upper portion thereof communicating with the interior of the arm 4. 75 The lower portion of the link is pivotally mounted within an eye 11 extending upwardly from a dome-shaped cap 12. The link opens into this eye and the eye, in turn, opens through a passage 13 into the cap 12. 80

Suspended from cap 12 is a cylindrical contact member 14 having diametrically opposed openings 15 into which are sprung fingers 16 provided at the ends of a spring cross strip 17. This cross strip has a bail 18 85 connected thereto and is also formed of a central opening 19.

The lower end of the tubular member 14 is closed by a cap 20 provided with vent openings 21 and extending downwardly 90 from the center of this shaft is a pin 22 connected to a plug 23 which is secured within the upper end of a tubular conducting member 24. This conducting member is adapted to be suspended within the building structure A and, in Figure 1 it has been shown extending downwardly through three floors, there being openings 25 in these floors whereby the member 24 is free to swing to a limited extent. For the purpose of covering 100

the openings 25 caps 26 can be secured to the member 24 as shown in Figure 1.

This member 24 is provided close to the ceiling of each room through which it extends with funnel-like intake arms 27 opening downwardly. Thus any hot gases rising in any one of the rooms will be free to flow into these arms and thence upwardly through the tubular member 24. At the upper end of this tubular member are outlet arms in the form of arcuate tubes 28 through which the rising hot gases will escape. These arms have their outlets close to fuses 29 which are interposed between the lower end portion of the tubular member 14 and spring arms 30 which are secured at their upper ends to the members 14. Contact lugs 31 are connected to the inner faces of the spring arms 30 and project into openings 32 formed in the tubular member 14. Springs 33 are connected to the arms 30 and serve to facilitate movement of these arms toward each other when one or both of the fuses 29 are melted.

Arranged within the tubular member 14 are smaller tubular contact members 34 each of which is similar in construction to the member 14 and has a cross strip 35 provided with a bail 36, these corresponding with the strip 17 and the bail 18. The contact members 34 are arranged one within the other but are out of contact. A conducting wire 37 or the like is connected to the bail 18 of the outer contact member 14 and to the bail 35 of the contact member 34 which is second from the inside. Another conducting wire 38 or the like is connected to the two remaining bails. The contact wires 37 and 38 are extended into the eye 11 and thence through the link 9 to the hook 8. These wires are insulated from each other and are extended longitudinally within the arm 4 and thence through the opening 7 through brackets 3 and through the tube or pipe 1 into the housing 39. This housing can be located at any point desired. A battery 40 can be arranged within the housing and one terminal of this battery is connected to one terminal of a switch 41 while the terminal of the switch is connected to the wire 37. Wire 38 is connected to one terminal of an electromagnet 42 and the other terminal of this electromagnet is connected to the battery 40. Thus it will be seen that, when the switch 41 is closed, the contact of any two members 34 and 14 due to oscillation of the members will result in closing the circuit to the magnet 42.

An armature 43 is arranged adjacent magnet 42 and is adapted to be engaged by a finger 44 extending from a spring strip 45 connected to one lead 46 of an electric circuit. A contact 47 is located at one side of the strip 45 but as long as finger 44 is bearing laterally against the finger 43 strip 45 is held away from this contact 47. Contact 47 is electrically connected to one terminal of a

switch 48. The other terminal of the switch is electrically connected, as at 49, to a signal device which can be in the form of a light 50 and a bell 51. The light and the bell can be located wherever desired. A lead 52 of the electric circuit last referred to is extended to the light 50 and to the bell 51, it being understood that a transformer 53 can be employed if desired in connection with the bell.

Assuming that the parts are positioned as illustrated in Figure 6 it will be apparent that, in the event of a fire in any one of the rooms in which the tubular member 24 is located the hot gases will flow upwardly through the tubular member and be directed by one or both of the tubular arms 28 against the fuses 29. One or both of these fuses will be melted, and as a result, the arms 30 will shift toward each other and cause one or both of the lugs 31 to bear against the next adjoining tubular member 34. Thus a circuit will be completed through the wires 37 and 38 and the magnet 42 with the result that the armature 43 will be attracted by the magnet. Consequently finger 44 will be released and the springs 45 will snap into engagement with the contact 47. This will close the circuit to the light 50 and the bell 51, both of which receive their power from the outside electric circuit indicated generally at 54.

Wires or cords 55 can be stretched across the windows and doors of the structure A and attached to the tubular member 24. Consequently should a person attempt to enter the structure through any one of the windows or doors one or more of these cords or wires will be shifted and will pull on the member 24 so as to move it out of normal position. This will result in agitation of the tubular members 14 and 34 which will come into contact and close a circuit thereby operating the alarm in the same manner as has already been described. By providing several of the tubular members 34 within the member 14 a circuit will be established when the members are agitated even though a foreign substance should become lodged between a couple of the members. In other words should one or two of the members be held against movement by some foreign substance or by any other cause, the remaining movable member or members will shift relative thereto and establish a circuit when they come into contact therewith.

When it is desired to render the alarm inoperative the switches 41 and 48 can be thrown so as to break the circuits.

It is to be understood that any desired number of arms 4 and their supporting brackets 3 can be used and a tubular member 24 with parts associated therewith can be suspended from each of these arms. In large structures it is desirable to have a number of these suspended tubular members 24 so that one of them will extend downwardly

through each vertical series of rooms in the structure.

What is claimed is:

1. In apparatus of the class described a circuit closer including a supporting cap, a tubular contact member suspended therefrom, a tubular contact member concentrically disposed within the first named member and mounted for oscillation relative thereto, one contact member being electrically connected to one terminal of a circuit and the remaining contact member being electrically connected to the other terminal of the circuit, spring arms carried by the outer contact member, means thereon adapted when released from normal position, to contact with the inner contact member, thereby to close a circuit between the members, a spring connection between the arms extending diametrically through but out of contact with all of the contact members, fusible means interposed between each arm and the outer contact member for holding the arm against actuation by the connecting spring, and means for oscillating the tubular contact members to close a circuit therethrough.

2. A circuit closer including an outer tubular member, spring arms connected thereto, a tubular supporting link, a cap connecting said link to one end of the tubular member, a closure for the other end of the tubular member, concentric normally spaced tubular contact members mounted for independent oscillation, alternate members being connected to one terminal of a circuit and the remaining members being connected to the other terminal of said circuit means for agitating the tubular members to close a circuit therethrough, fusible means for holding the spring arms normally spaced from the outer tubular member, a spring connection between the arms extending diametrically through all of the tubular members but out of contact therewith, and means carried by the spring arms for actuation by the spring connection when the fusible means are removed, for electrically connecting two of the tubular members to close the circuit therebetween.

In testimony that I claim the foregoing as my own, I have hereto affixed my signature.

WILLIAM J. MULLIGAN.
